*Design No. 461**David Thomson's design for Portable grate.**Assigned to Newmarket Iron Foundry. Patented June 1st 1852.**Fig. 1**Fig. 2**Fig. 3*Des. 461

David Thomson of Boston, Mass
Assignor to
New Market Iron Foundry
Letters Patent No 1461. Dated June 8th 1852.

The schedule referred to in these Letters Patent and making part of the same

To all ^{Persons} to whom these Presents shall come:

Be it known that I, David Thomson of Boston, in the County of Suffolk and State of Massachusetts have produced a new and original design for the front of a portable grate, and I hereby declare that the said new design is fully described and represented in the following specification and accompanying drawings to which reference is hereinafter made.

The figures of the accompanying plate of drawings represent my new design.

Fig: 1. is a front elevation of the same. Fig: 2, is a vertical section taken in the plane of the line A B Fig: 3, is a vertical section taken in the plane of the line C D.

The top of the front is ornamented with the sunken panels a, and b, surrounded by the mouldings c. c. &c. In the panels a, a, are the raised elliptical figures d, d, and in the panel b, the elongated figure e. Around and between these panels are the raised mouldings f. f. The sides are ornamented with the leaf scroll g. g. g.

Des. 461

which rest on the bases h, h. On these bases rest the columns i-i-i from which spring the arched mouldings k, k, &c

The blower is ornamented with the leaf work & raised on the rays m, m.

Having thus described my new design I shall state my claim as follows:-

What I claim as my production and desire to have secured to me by Letters Patent, is the new design consisting of the sunken panels, leaf scrolls and ornamental mouldings, herein above described and represented in the drawings, for the front of a portable grate.
